United States Patent

Des. 241,224
Patented Aug. 31, 1976

241,224

BOTTLE OR THE LIKE

Gordon Delbert Holmes, Scarborough, Ontario, Canada, assignor to Gold Seal Company, Bismarck, N. Dak.

Filed Oct. 16, 1974, Ser. No. 515,179

Term of patent 14 years

Int. Cl. D9—01

U.S. Cl. D9—33

FIG. 1 is a front elevational view of a bottle or the like showing my new design;

FIG. 2 is an elevational view looking from the right of FIG. 1;

FIG. 3 is a rear elevational view;

FIG. 4 is an elevational view looking from the left of FIG. 1;

FIG. 5 is a top plan view; and,

FIG. 6 is a bottom plan view thereof.

I claim:

The ornamental design for a bottle or the like, substantially as shown.
